SELECTIVE CODE RECEIVER

Harry E. Hershey, Oak Park, Ill., assignor, by
mesne assignments, to Associated Electric Lab-
oratories, Inc., Chicago, Ill., a corporation of
Delaware

Application May 17, 1929, Serial No. 363,875

7 Claims. (Cl. 177—353)

The present invention relates in general to "im-
provements in selective code receivers". The main
object of the invention is the design of a receiving
device which may be used in conjunction with
5 wireless receiving apparatus and which will re-
spond to and record only a predetermined signal
such as an S. O. S. distress call.

A particular feature of the invention is the
provision of a chain of counting relays which is
10 completely operated only by the S. O. S. signal
of three dots, three dashes, and three dots.

Another feature of the invention lies in the
system of control relays which discriminate be-
tween the dots and dashes of a received signal.

15 Another feature is the provision of means for
restoring the receiver to normal in case the entire
signal is not received as a single letter.

A still further feature of the invention lies in
the means for releasing the operated portion of
20 the relay chain at any point during the recording
of the signal if the dots and dashes of the signal
are not received in proper number and sequence.

Other features pertaining to the detailed cir-
cuit arrangement will be apparent from the fol-
25 lowing specification.

A complete understanding of the invention may
best be had from the following detailed explana-
tion when read in connection with the accom-
panying drawing, comprising one figure only,
30 which shows by means of the usual schematic
diagram the complete circuit of the S. O. S. re-
ceiver. The wireless receiving set has been indi-
cated at RS and not shown in detail, as these
receivers are well known in the art. The receiver
35 is arranged to be used with any of these sets
having a plate circuit suitable for operating the
plate relay P. This plate relay may be adjusted
to operate with the particular set to be used. The
minor switch M is the standard ten-point minor
40 switch well known in automatic telephony.

As is well known in the art, a complete S. O. S.
signal is transmitted as one letter, and the oper-
ation of the receiver depends upon the correct
transmission of the signal in accordance with this
45 practice. A distinct pause such as is used to sepa-
rate the letters of the word in telegraphy will
allow the receiver to release. However, the dashes
of the signal may be made as long as desired by
the operator transmitting the signal without
50 interfering with the operation of the receiver in
any way.

The complete operation of the receiver upon
the receipt of an S. O. S. signal of three dots, three
dashes, and three dots will first be explained.
55 The first dot of the signal is received by the re-

ceiving apparatus RS, which in turn momentarily
operates plate relay P. At its make contact 9,
relay P closes an obvious circuit for relays 2 and 3
in multiple. Relay 3 is slow to operate and is
adjusted to respond to the dash impulses of the 60
signal but will not respond to the dot impulses.
Relay 2 operates and at contact 10 closes an obvi-
ous circuit for relay 1 which is made slow to
release and is adjusted to remain operated during
the complete signal, provided the entire signal is 65
received as a single letter. Relay 2 also closes a
circuit from ground, contact 11, resistance 12,
winding of relay 4, back contact 13 of relay 3,
resistance 14, to battery. Relay 4 operates but is
quickly released due to the opening of contact 11 70
of relay 2 which is deenergized at the end of the
dot impulse by the release of the plate relay P.
Before relay 4 releases, however, it closes a cir-
cuit from battery, resistance 14, back contact 13
of relay 3, winding of relay 4, resistance 12, con- 75
tact 15, resistance 16, winding of relay 5, to ground.
Relay 5 operates in this circuit after relay 2 re-
leases to remove at its armature 11 the shunt
around relay 5 and at contact 17 short circuits
the winding of relay 4. 80

The operation of relay 5 also closes a circuit
from ground, make contact 18 of relay 5, conductor
95, back contact 19 of relay 21 of dot group #1,
winding of relay 20, to battery. Relay 20 oper-
ates and at contact 40 closes a circuit from bat- 85
tery, winding of relay 20, contact 40, winding of
relay 21, back contact 78 of relay 6, back contact
62 of relay 26, back contact 77 of relay 6, back
contact 58 of relay 32, make contact 80 of relay 1,
to ground. When relay 5 releases due to the 90
opening of contact 15, the ground shunt is re-
moved from the winding of relay 21, allowing it
to operate in series with relay 20 in the above-
traced circuit. At contact 41 the impulsing lead
95 is extended to relay 22 of dot group #2. 95

When the second dot of the S. O. S. signal is
received by the receiving set RS, relay P is again
momentarily energized and in turn causes the
momentary energization of relays 2, 4, and 5 in
the above-described manner. The closing of con-
tacts 18 of relay 5 completes a circuit from ground,
contact 18, impulse lead 95, contact 41 of relay 21,
contact 43 of relay 23, winding of relay 22, to
battery. Relay 22 operates and at contacts 42 100
closes a circuit from battery, winding of relay 22,
contact 42, winding of relay 23, to ground at con-
tact 80 of relay 1 over the same path as hereto-
fore traced for the operation of relay 21. Upon
the release of relay 5, relay 23 operates and at 105
110

contacts 44 extends the impulsive lead 95 to relay 24 of dot group #3.

The third dot of the S. O. S. signal is received in the same manner as described for the first 5 and second dots. In this case relays 24 and 25 of dot group #3 are operated. At its contact 47 relay 25 transfers the impulsive lead 95 to relay 32 of dot group #4. At contact 59 it closes a locking circuit for the relays of the first three dot 10 groups independent of contact 62 of relay 26. This locking circuit extends from ground, contact 80 of relay 1, back contact 58 of relay 32, back contact 77 of relay 6, contact 59 of relay 25, to the windings of relays 25, 23, and 21 in multiple. The 15 first three dots of the S. O. S. signal have now been received and registered.

When the first dash of the signal is next received, relay P again operates and in this case remains operated a sufficient length of time to 20 operate relay 3 in multiple with relay 2. At its back contact 13, relay 3 opens the circuit of relays 4 and 5 to prevent the operation of these relays and the registering of another dot at this time. At contact 79 relay 3 closes a circuit from 25 ground, contact 79, conductor 96, back contact 64 of relay 27, winding of relay 26, to battery. Relay 26 operates and at contact 63 closes a circuit from battery, winding of relay 26, contact 63, winding of relay 27, back contact 76 of relay 6, contact 30 of relay 1, to ground. At the end of the dash impulse relay 3 releases due to the opening of contact 9 of relay P and at contact 79 removes the ground shunt from relay 27, allowing it to operate in series with relay 26 in the above-traced circuit. At contact 65 relay 27 extends the impulsive lead 96 to relay 28 of dash group #2. The second dash of the signal operates relays 28 and 29 of dash group #2 in the same manner as described above for the operation of relays 26 and 40 27. Relay 29, at its contact 68, extends the impulsive lead 96 to relay 30 of dash group #3.

When the third dash of the signal is received, relays P and 3 operate as heretofore described. Relay 3 now closes a circuit from ground, contact 79, conductor 96, contact 65 of relay 27, contact 68 of relay 29, back contact 71 of relay 31, winding of relay 30, to battery. Relay 30 operates and at contact 70 prepares a circuit for relay 7 as will be described later. At contact 69 a circuit is closed from battery, winding of relay 30, contact 69, winding of relay 31, back contact 76 of relay 6, contact 80 of relay 1, to ground. When ground is removed from the impulsive lead 96 due to the release of relay 3 at the end of the dash impulse, relay 31 operates in series with relay 30 in the above-traced circuit. At contact 72 the impulsive lead 96 is extended to relay 38 of dash group #4. The function of relays 38 and 39 of dash group #4 will be explained later. At contact 75 relay 31 closes a locking circuit for the relays of the first three dot groups independent of contact 58 of relay 32 of dot group #4. This locking circuit extends from ground, contact 80 of relay 1, contact 60 of relay 25, contact 75 of relay 31, contact 65 78 of relay 6, to the windings of relays 21, 23, and 25 in multiple. The first three dots and the three dashes of the S. O. S. signal have now been received and registered.

When the fourth dot of the S. O. S. signal is 70 next received, relay P operates and in turn operates relays 2, 4, and 5 in the manner already described for the first three dots. The operation of relay 5 closes a circuit from ground, contact 18, impulse lead 95, contact 41, contact 44, contact 75 47, back contact 49 of relay 33, winding of relay

32, to battery. Relay 32 operates and at contact 48 closes a circuit from battery, winding of relay 32, contact 48, winding of relay 33, contact 80 of relay 1, to ground. The opening of contacts 58 at this time is without effect as a substitute locking circuit for the relays of the first three dot groups has been closed at contacts 60 and 75. When ground is removed from impulse lead 95 at the end of the dot impulse, relay 33 operates in series with relay 32 in the above-traced circuit. At contact 50 the impulse lead 95 is extended to relay 34 of dot group #5. When the next dot of the signal is received, relays 34 and 35 of dot group #5 are operated in the same manner as relays 32 and 33 of dot group #4. The operation of relay 35 extends the impulsive lead 95 to relay 36 of dot group #6.

When the last dot of the S. O. S. signal is received, relays P, 2, 4, and 5 operate in the same manner as heretofore described. The operation of relay 5 closes a circuit from ground, contact 18, impulse lead 95, contact 41 of relay 21, contact 44 of relay 23, contact 47 of relay 25, contact 50 of relay 33, contact 53 of relay 35, back contact 55 of relay 37, winding of relay 36, to battery. Relay 36 operates and closes a circuit from battery, winding of relay 36, contact 54, winding of relay 37, contact 80 of relay 1, to ground. When ground is removed from the impulse lead 95 due to the deenergization of relay 5 at the end of the dot impulse, relay 37 operates in series with relay 36 in the above-traced circuit. At contact 57 it closes a circuit from ground, contact 80 of relay 1, contact 70 of relay 30, contact 57 of relay 37, contact 84 of relay 8, winding of relay 7, to battery. Relay 7 operates and at contact 81 closes an obvious circuit for the stepping magnet 86 of the minor switch M. Magnet 86 operates and moves wiper 88 to the first bank contact 89. This closes a circuit from ground, wiper 88, bank contact 89, alarm lamp 90, to battery, lighting the lamp to indicate that an S. O. S. signal has been received. The pause following the transmission of the complete S. O. S. signal allows relay 1 to release and open its contact 80, thereby removing ground from the holding leads, and allowing all the relays of the receiver to restore to normal.

It will be appreciated that there is a remote possibility of impulses due to static being received 125 in combination with telegraph signals in the proper sequence and number to operate the chain of the registering relays. In view of this possibility, the first three bank contacts of the minor switch M are connected only to a lamp 90. Thus the first three signals received will bring in only a visual alarm. The remaining bank contacts, 4 to 10 inclusive, are wired to a lamp 91 and also to a bell 92. Allowance is thereby made for a maximum of three possible false alarms during 130 the time that the operator is off duty. Should an S. O. S. call be received during this period, the minor switch M will be stepped past the fourth bank contact due to the continuous repetition of the signal. Thus an audible alarm will be sounded 135 calling the operator to duty. The minor switch may be released by the operator at any time by depressing the non-locking release key 94, thereby closing an obvious circuit for the release magnet 87.

The manner in which the relay chain is automatically released should the received signal deviate at any point from the prescribed S. O. S. signal of three dots, three dashes, and three dots 140 will now be explained. It will first be assumed 150

that the entire S. O. S. signal is not transmitted as one letter, but that a pause occurs at some point between the impulses of the signal. In this case the pause will allow relay 1 to release, opening contact 80 and thereby removing ground from the locking circuits of the relay chain. This allows all relays to release and the receiver to restore to normal.

It will now be assumed that a dash is received before the first three dots of the signal have been registered. In this case the dash impulse operates relays 26 and 27 in the manner already described. The operation of relay 26 opens contact 62, thereby removing the holding ground from those relays of the dot recording group which have already been operated. This allows the relays of the dot recording group to be released. The relays 26 and 27 are maintained operated until the end of the signal when the usual pause will release relay 1 and restore the receiver to normal.

If four successive dots should be received before the first dash of the signal is received, the fourth dot will operate relays 32 and 33 in a manner already described. The operation of relay 32 opens contact 58, which removes the holding ground from the relays of the first three dot groups, allowing them to release. In this case relays 32 and 33 are maintained operated until the end of the signal when the usual pause will allow relay 1 to release, thereby restoring the receiver to normal. The next possibility to be considered is that of a fourth dash being received after the first three dots and the three dashes of the signal have been registered. The receipt of the fourth dash will operate relays 2 and 3 in the same manner as already described for the first three dashes. The operation of relay 3 closes a circuit from ground, contact 79, contact 65 of relay 27, contact 68 of relay 29, contact 72 of relay 31, winding of relay 38, to battery. Relay 38 operates in this circuit and at contact 73 closes a circuit from battery, winding of relay 38, contact 73, winding of relay 39, contact 80 of relay 1, to ground. When ground is removed from the impulse lead 96 at the end of the dash impulse, relay 39 operates in series with relay 38 in the above-traced circuit. At contact 74, an obvious circuit is closed for the slow-to-release relay 6. Relay 6 operates and at contact 76 removes holding ground from the relays of the first three dash groups. At contacts 77 and 78 relay 6 removes holding ground from the relays of the first three dot groups and all relays of the first three dot groups and the first three dash groups are thereby released. Relays 38 and 39 are maintained energized until the end of the signal when the usual pause allows relay 1 to release, thereby restoring the receiver to normal.

The only other possibility which might tend to bring in a false alarm is the receipt of a signal consisting of three dots, three dashes, and four dots. Upon the receipt of the sixth dot, contact 57 is closed, thereby closing a circuit for relay 7 as already described. However, the receipt of the seventh dot places ground on the impulse lead 95 which extends through contact 41 of relay 21, contact 44 of relay 23, contact 47 of relay 25, contact 50 of relay 33, contact 53 of relay 35, contact 56 of relay 37, winding of relay 8, to battery. As relay 7 is made slow to operate, relay 8 is energized in this circuit and opens contact 84 before relay 7 has had time to energize. Relay 8 closes a locking circuit for itself extending from ground, contact 80 of relay 1, contact 76 of relay

6, resistance 82, contact 83 of relay 8, winding of relay 8, to battery. Relay 8 remains locked in this circuit until the receiver is restored to normal by the release of relay 1 at the end of the signal.

If the last three dots of the signal were followed by a dash, relays 38 and 39 would be operated as previously explained. Relay 39 at contact 74 closes the circuit for relay 6 which operates and at contacts 76 and 78 opens the holding circuits of the relays of the first three dot groups and the first three dash groups which thereupon release. Relay 30, in releasing, opens contact 70 thereby opening the circuit of relay 7 which has not had time to operate. The relays of the last three dot groups and of the fourth dash group remain locked up until relay 1 releases during the abnormal pause between signals.

From the foregoing, it will be seen that the only possible signal or combination of impulses which can operate the chain of registering relays to bring in an alarm is the S. O. S. signal of three dots, three dashes, and three dots, transmitted as one letter. The possibility of this signal being duplicated by a combination of static and telegraph signals is very remote.

Although only a particular application of the invention has been described in the foregoing specification, it is apparent that the receiver could be arranged to respond only to some signal other than an S. O. S. call without departing from the spirit of the invention.

Having described the invention, what is thought to be new and is desired to have protected by Letters Patent will be set forth in the appended claims.

What is claimed is:

1. In a receiving device, a counting apparatus, means for causing a progressive operation of said apparatus responsive to successive spaced signals of two kinds forming a predetermined code, an alarm, means for operating said alarm upon the complete operation of said apparatus in response to said code, a second alarm, and means for operating said second alarm responsive to a predetermined number of complete operations of said apparatus.

2. In a receiving device, dot and dash counting means completely operable responsive to a particular dot and dash code signal only, an alarm signal, means responsive to the complete operation of said counting means for operating said alarm signal, a second alarm signal, and means responsive to a predetermined number of complete operations of said counting means for operating said second alarm signal.

3. In combination, dot and dash counting means completely operable only by dot and dash impulses in accordance with a predetermined code, a stepping switch, means responsive to each complete operation of said counting means for advancing said switch one step, a visual signal operated as soon as said switch is operated off-normal, and an audible alarm signal operated when said switch has been advanced to a predetermined position.

4. In combination, dot and dash counting means completely operable only by dot and dash impulses in accordance with a predetermined code, a stepping switch, means responsive to each complete operation of said counting means for advancing said switch one step, a visual signal operated as soon as said switch is operated off-normal, an audible alarm signal operated when said switch has been advanced to a predetermined position.

mined position, and manually operated means for releasing said switch at any time.

5. In combination, dot and dash counting means completely operable only by dot and dash impulses in accordance with a predetermined code, means for registering the number of complete operations of said counting means, a visual signal operated responsive to the registering of the first operation of said counting means and 10 an audible alarm signal operated when a predetermined number of said operations have been registered.

6. In a selective code receiver, three groups of register relays, means for operating each group 15 in accordance with impulses of a predetermined code signal, means for insuring the sequential operation of said groups of relays including a releasing circuit for the relays of the first group controlled by the first relay in the third group,

20

and a holding circuit for the relays of said first group controlled by the last relay in the second group.

7. In a selective code receiver, three groups of register relays arranged to be operated in 80 sequence, means for operating each group in accordance with impulses of a predetermined code signal, a holding circuit for the relays of the first group completed when said first group is completely operated to prevent release of the 85 relays of the first group while the relays of the second group are operated, a substitute locking circuit for the relays of said first group completed by the last relay in the second group to prevent release of said relays while the relays of the 90 third group are being operated, and contacts on the first relay of the third group for opening said first locking circuit.
